UNITED STATES PATENT OFFICE.

NAPOLEON GRANDCHAMP, OF RAYMOND, WASHINGTON, ASSIGNOR OF ONE-HALF TO
CHARLES MYERS, OF RAYMOND, WASHINGTON.

OPERATING MECHANISM FOR BOLT HEADERS AND SHEARS.

1,241,728.

Specification of Letters Patent.

Patented Oct. 2, 1917.

Application filed October 5, 1916. Serial No. 123,996.

To all whom it may concern:

Be it known that I, NAPOLEON GRANDCHAMP, a citizen of the United States, residing at Raymond, in the county of Pacific and State of Washington, have invented 5 a new and useful Operating Mechanism for Bolt Headers and Shears, of which the following is a specification.

The present invention relates to a machine for heading and cutting bolts, although it can be used as a punch also, and it is the object of the invention to provide a machine of that character having, first, novel means for holding and heading a bolt, 15 second, novel means for cutting off the bolts or shearing other objects and, third, novel means for actuating the machine to obtain a maximum power with minimum manual effort.

With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a side elevation of the machine.

Fig. 2 is a top plan view thereof.

Fig. 3 is an enlarged section taken on the line 3—3 of Fig. 1, with the bolt holding cap swung open.

Fig. 4 is an enlarged sectional detail taken on the line 4—4 of Fig. 2.

Fig. 5 is an enlarged sectional detail taken on the line 5—5 of Fig. 1.

The frame of the machine embodies a horizontal body 1 supported by suitable legs 2, preferably connected by a tie rod 3. Se- 45 cured to or integral with one side of the body 1 is an upstanding relatively thick side plate 4, and an opposite upstanding side plate 5 is secured to the other side of the body 1 to complement the plate 4, said plates 50 4 and 5 having the upwardly opening recesses 6 and 7 to receive a bolt or other object to be cut in two. The plate 5 is provided at its upper edge with lugs 8 projecting toward and abutting against the upper portion of the plate 4, said lugs being dis-

posed at opposite sides of the recesses 6 and 7, and being secured by screws 9 or other suitable means to the plate 4 to provide a rigid guide for an elongated slide 10 which moves snugly between the plates 4 and 5 upon the upper edge of the body 1 under the lugs 8. The slide 10 has an upwardly opening recess 11, and a shear plate 12 is inset in and secured to the inner surface of the plate 4 in front of the recess 6 and has 60 a rear upright cutting edge projecting into the recess 6. A shear plate 13 is inset in and secured to that side of the slide 10 facing the plate 4, and the shear plate 13 rests against and is slidable along the shear plate 12. The shear plate 13 has an upwardly opening recess 14 providing a cutting edge at the rear of said recess and coöperating with the cutting edge of the plate 12 to shear the bolts or other objects placed in the recesses 6, 11, 14 and 7, the slide 10 being 65 moved forwardly to complete the cut.

A plate 15 is inset in and secured to the plate 4 in rear of the recess 6 and rests flatly against the plate 13, the plates 4 and 15 having registering apertures 16, and the slide 10 and plate 13 having registering apertures 17 to register with the apertures 16, while the plate 5 has an opening 18 opposite the apertures 16. A bolt, cable or other object can 80 be inserted in the apertures 16 and 17 to be sheared or severed, or otherwise acted upon when the slide 10 is moved forwardly.

The forward end of the body 1 carries a clamp for holding a bolt during the heading 90 operation, and for this purpose, the forward end of the body 1 has an upwardly facing clamp member 19 to which a companion clamp member or cap 20 is hinged at one side, as at 21, to swing open to one side and 95 to swing to closed position above the member 19, as seen in Fig. 4. A handle 22 is pivoted to the free portion of the cap 20, and has a lug 23 seatable upwardly against a shoulder 24 with which the member 19 is 100 provided, whereby the handle can be swung toward the body 1 for moving the cap 20 tightly into position. The member 19 and cap 20 are each provided with an angular recess 25 into which a removable die 26 is 105 fitted the same having a longitudinal concaved groove or channel 27 for receiving one half of a bolt placed therein. The forward ends of the recesses 25 are reduced, as at 28, to receive the reduced forward ends 110

29 of the dies 26, and to provide shoulders 30 for limiting the forward movement of the dies, said dies being removable and replaceable by other dies having channels 27 of different sizes, whereby bolts of various diameters can be headed.

The forward end of the slide 10, designated 31, has a socket 32 for receiving the shank 33 of a socketed heading die 34 which 10 is movable to and from the rear ends of the companion dies 26. The heading die 34 is also removable and replaceable by other heading dies having different sizes and shapes of sockets whereby different sizes and 15 shapes of heads can be formed.

To head a bolt, the cap 20 is swung open, and the bolt is placed in the die 26 of the member 19, with its rear end projecting the proper distance from said die. The cap 20 20 is then swung over the member 19, and the handle or lever 22 manipulated, to force the cap 20 downwardly whereby the bolt is clamped tightly between the dies 26. The slide 10 is then moved forwardly, whereby 25 the heading die 34 is brought forcibly against the red-hot end of the bolt, whereby to force the metal to fill the socket of the heading die, thereby producing the head of the bolt. The die 34 is then retracted with 30 the slide 10, and the cap 20 swung open so that the bolt can be removed. It is to be noted that when the bolts are headed, the shears is also operated, so that the bolts can be cut off to the desired length by the same 35 operation of the machine.

As effective means for forcing the slide 10 forwardly for heading the bolt and cutting a bolt or another object, there is provided two pairs of toggle links 35 disposed side by 40 side, and having their remote ends pivoted to the rear end of the slide 10 and the rear end of the body 1, as at 36 and 37 respectively. The joint or pivot 38 which connects the toggle links is engaged with a floating 45 lever 39 which is connected to the body 1 between the pivots 36 and 37. Thus, a pair of side links 40 have their upper ends pivoted, as at 41, to the floating lever 39, and have their lower ends pivoted to the opposite 50 sides of the body 1, as at 42. The lever 39 has an upwardly projecting arm 43 between the pivots 38 and 41, and a pair of links 44

connect the arm 43 with a hand lever 45 having the pivot 37 as a fulcrum. The lever 45 has a fork 46 extending over the rear 55 links 44 and engaging the pivot 37. When the lever 45 is swung forwardly, the links 44 are moved forwardly, and the arm 43 is swung in the same direction, thus raising the pivot or joint 38 of the toggle links 35, 60 so that the forward links 35 are pulled rearwardly to retract the slide 10. When the lever 45 is swung rearwardly, the links 44 and arm 43 are moved rearwardly, and this will forcibly depress the pivot 38, to move 65 the links 35 toward a straight line position, whereby to move the slide 10 forwardly with great force.

The entire machine is compact and comparatively simple in construction, and is 70 practicable and serviceable in use.

Having thus described the invention, what is claimed as new is:—

1. A machine of the character described embodying a body, a slide movable along the 75 body to operate upon a bolt or other object, the body having a guide for said slide, a pair of toggle links having their remote ends pivoted to the slide and body, a floating 80 lever pivoted to the joint of said links, and a link connecting said floating lever and body.

2. A machine of the character described embodying a body, a slide movable along the body to operate upon a bolt or other object, 85 the body having a guide for said slide, a pair of toggle links having their remote ends pivoted to the slide and body, a floating lever pivoted to the joint of said links, a link connecting 90 said floating lever and body, the floating lever having an arm projecting therefrom, a hand lever having as its fulcrum the pivot between the body and the respective toggle link, and a link connecting the hand lever and said arm of the floating 95 lever.

In testimony that I claim the foregoing as my own, I have hereto affixed my signature in the presence of two witnesses.

NAPOLEON GRANDCHAMP.
